UNITED STATES PATENT OFFICE

2,035,568

BRACKET

John Pudliner, Allentown, Pa., assignor to Brey
& Krause Manufacturing Company, Allentown,
Pa., a corporation of Pennsylvania

Application April 2, 1934, Serial No. 718,695

2 Claims. (Cl. 248—225)

This invention relates to an improved bracket for securing fixtures of various kinds to a supporting structure. More specifically the present invention relates to brackets for securing bath room fixtures of various kinds or the like to the walls of the room, though it may be used for many other purposes.

In Patent Number 1,897,913, a bracket is disclosed for securing bath room or other fixtures to plastered or similar walls, which bracket can be used to attach towel bars, tumbler holders, soap dishes and the like to walls. While said arrangement is satisfactory under ordinary circumstances, it does not provide for supporting the weight of the fixture largely independently of the fastening means. The present invention constitutes an improvement on said patent by providing the bracket with a relatively wide boss presenting a large bearing area to a relatively large area formed on a portion of the bracket with which it contacts. In this way any load on the fixture is distributed over a large area on the bracket, and use can be made of the enlarged area of the bracket boss to relatively widely space the fastening devices that are applied from the end thereof so that the fastening device can exert its holding power at widely spaced points and at parts of the wall that are unaffected by the entry of fasteners at closely spaced points. A rigid mounting of the bracket is thus obtained.

It is therefore a primary object of the present invention to devise a bracket of the above mentioned character that will provide a rigid support for a fixture by means of widely spaced fastening elements and that will at the same time permit ready interchangeability of fixtures.

A further major object of the present invention resides in the provision of a securing bracket that will permit a more substantial association with a supporting structure with a fixture and that will at the same time appear to present a unitary construction when associated with the fixture.

A further object of the present invention resides in the provision of a bracket which has surfaces formed to match with surfaces on the fixture to prevent rotation of the fixture relative to the bracket.

A further object of the present invention resides in the provision of a securing bracket which presents a wide base area for contact with the fixture.

Still further objects of the present invention will appear from the following description and

appended claims when studied in connection with the accompanying drawing wherein:

Figure 1 is a top plan view of the bracket in its final assembled position with a soap dish attached thereto, the wall being shown in section.

Figure 2 is a front elevational view, of the device shown in Figure 1.

Figure 3 is a sectional view taken on line 3—3 of Figure 1 looking in the direction indicated by the arrows.

Figure 4 is a fragmentary view taken from the rear of the soap dish illustrated in Figure 1 showing the flattened end provided on the integral shank formed on the fixture.

Figure 5 is a front view of the bracket with the soap dish removed in order to show the arrangement of the several apertures.

With reference to the drawing, the numeral 10 designates generally the bracket, forming the present invention, said bracket is secured to a wall 11 in a manner to be hereinafter described and is adapted to receive a bath room or other fixture such as soap dish 12.

Bracket 10, formed by casting or in any other suitable manner, is provided with an enlarged base 13 and an elongated outwardly projecting slightly tapering boss 14. Base 13 is furthermore provided with sloping marginal edges 15 which are adapted to lie in intimate contact with the plaster or other material 16 forming the wall surface. Boss 14 is provided with a pair of apertures 17 and a further aperture 18 between apertures 17. These apertures 17 and 18 extend completely through bracket 10 at its thickest portion.

The walls of apertures 17 are of less diameter than adjacent wall 11 providing inclined shoulders 19 to engage the tapering heads 22 of wood screws 23. The shanks 24 of screws 23 project through the smaller apertures 25 beyond shoulders 19 and are secured to a wooden or similar support 26 forming a part of the plastered wall of the building. When screws 23 are drawn to their final position the edges 27 of the sloping sides 15 of bracket 10 will be drawn tightly against surface 16 and bracket 10 will be rigidly secured upon wall 11. In addition to drawing the bracket 10 tightly against wall 11 the screws 23 will prevent rotation of the bracket 10 since they are secured to the wall 26 in relatively widely spaced relation. Although bracket 10 has been described as being secured to a wall 11, it will be clear that the bracket may be secured to any desired support by suitable fastening means inserted through apertures 17.

In the preferred embodiment of the invention

illustrated in the drawing, the walls of apertures 18 are formed to provide a non-circular aperture 33 adjacent the wall. Aperture 33 receives a complementarily formed non-circular extremity 34 of shank 32 to prevent the rotation of the fixture associated with the bracket 10.

The fixture such as soap dish 12 is furthermore provided with a portion 35 having an outer surface matching exactly the outer surface of boss 14 of bracket 10 so that when the fixture is in its final assembled position no line of demarcation between bracket and fixture is apparent. It will be readily appreciated from an inspection of Figure 2 that, when the portion 35 is in its final assembled relation with respect to boss 14, the apertures 17 and 18 will be completely concealed and a smooth and uninterrupted finished surface will meet the eye.

In order that the soap dish 12 may be retained against axial removal from aperture 18 the boss 14 on its lower unexposed side is suitably tapped at 36 to receive a set screw 37 which is adapted to pass through lower aperture 17 and threaded aperture 38 into contact with shank 32 of the fixture. The set screw is invisible in view of the fact that it is applied from the under side of boss 14.

Although in the preferred embodiment of the invention the bracket 10 is shown having a six sided base and an elongated oval boss 14 for receiving the fastening means and the shank of the fixture, it is to be understood that the invention may be embodied in other shapes and contours.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A bath room or similar fixture, comprising a bracket part and a fixture part, said bracket part having a plate-like base and a narrow elongated boss projecting substantially away from said base, a pair of fastener receiving apertures passing through said base in a direction normal to said base to non-rotatively secure the bracket part to a wall, said apertures opening within said boss, a non-circular recess formed in said bracket from the end of said boss, said fixture part having a non-circular shank fitting into said recess and a surrounding portion covering the end of said boss and said apertures, said fixture part having an external surface matching the external surface of said boss at the line of juncture between the bracket and fixture parts, and a set screw passing through a wall of said boss and engaging said non-circular shank to maintain the bracket and fixture parts in assembled relation. 5 10 15

2. A bath room or similar fixture, comprising a bracket part and a fixture part, said bracket part having a plate-like base and a narrow elongated boss projecting away from said base, a pair of fastener receiving apertures passing through said base in a direction normal to said base to non-rotatively secure said bracket part to a wall, a recess formed in said boss from the end thereof, said recess having non-circular wall portions, 25 30 35 said fixture part having a protruding shank slidably and non-rotatively disposed in said recess and having a portion in engagement with the end of said boss, said fixture part having exterior surfaces formed to match the external surfaces of said boss at the line of juncture between said bracket and fixture parts to present a smooth uninterrupted connection between the base of the bracket and the boss within which the bracket securing means are concealed. 40

JOHN PUDLINER.
